UNITED STATES PATENT OFFICE.

WALTER G. PREDEY, OF SAN FRANCISCO, CALIFORNIA.

CARBON FEEDING AND ADJUSTING MECHANISM FOR ARC LAMPS.

Application filed February 1, 1926. Serial No. 85,231.

My invention relates to improvements in mechanism for feeding and adjusting the carbons of arc lamps and the like whereby a pair of carbon electrodes are adjusted and maintained in arc producing relation.

The primary object of my invention is to provide an improved carbon feeding and adjusting mechanism for arc lamps.

Another object is to provide an improved mechanism adapted to facilitate the initial adjusting of carbons and to facilitate and obtain a saving in time in changing carbons and in resetting the carbon carriers of an arc lamp.

15 A still further object is to provide an improved power actuated feeding mechanism adapted to be normally operated by an electric motor whereby power may be positively applied to move the carbons simultaneously 20 at a very slow speed to maintain the correct relation of the carbons to produce an efficient arc.

25 A still further object is to provide an improved device of the character described adapted to be operated either manually or by power and adapted for quick manual adjustment.

30 A further object is to provide an improved construction wherein a power feeding mechanism is adapted to obtain a very great reduction of speed within a minimum of space.

35 A still further object is to provide an improved device of simplified construction which will be highly efficient in operation and which will facilitate the care and adjustment of the lamp.

40 I accomplish these and other objects by means of the improved device disclosed in the drawings forming a part of the present specification wherein like characters of reference are used to designate similar parts throughout said specification and drawings and in which,

45 Fig. 1 is a side elevation of my improved carbon feeding and adjusting mechanism.

Fig. 2 is a plan view of the device as disclosed in Fig. 1 of the drawings.

50 Fig. 3 is a front elevation, partly in section, of a carrier and shaft engaging means.

Fig. 4 is a side elevation of the carrier as shown in Fig. 3.

Fig. 5 is a broken front elevation of the shaft rotating mechanism.

Fig. 6 is a plan view of the mechanism shown in Fig. 5.

Referring to the drawings the numeral 1 is used to designate in general the frame of an arc lamp of the character used in the projection of motion pictures and the like. A 60 pair of shafts 2 and 3 are rotatably mounted upon the frame 1, said shafts extending longitudinally across the frame 1 and extending outwardly from one end thereof.

The shaft 2 is provided with right and left 65 hand threaded portions extending inwardly from the ends to substantially the middle of the frame, said threaded portions being arranged to be engaged in a manner herein-after more fully explained by a pair of carriers 4 each arranged to receive an arc carbon 6, said carbons being held in axial alignment to produce an arc in the well known manner. The carriers 4 extend transversely 70 across the frame 1 and are mounted in slid- 75 able engagement with the shaft 3.

The shaft 3 is threaded along the middle portion thereof, said threaded portion being engaged by a carrier 7 arranged to support a reflector 9 for projecting light from the arc produced between the carbons 6, said carrier being arranged to be moved longitudinally along the shaft by an appropriate rotation of said shaft. A knob 9 is provided upon the outwardly extending end of the shaft 3 whereby the shaft may be manually rotated to adjust the longitudinal position of the reflector relative to the carbons 6.

80 The carriers 4 are provided with bushings 11 slidably engaging the shaft 2 and movable freely over the threads thereon. Levers 12 are pivotally mounted upon the under sides of the carriers, said levers being movable in slots 13 to engage the threads of the shaft 2. The levers are arranged at an 85 angle equal to the pitch of the threads and are normally held in engagement with said threads by means of suitable springs 14 whereby a rotation of the shaft will cause the carriers to be moved longitudinally 90 therealong. Handles 16 are formed upon the outer ends of the levers 12, said handles extending outwardly whereby the levers may be pressed downwardly out of engagement.

with the threads, thereby permitting the carriers to be moved freely along the shaft in either direction independently of the rotation of the shaft 2, as shown in Figs. 3 and 4 of the drawings.

The shaft 2 is arranged to be rotated by power derived from a suitable electric motor 17 mounted upon the frame 1 and arranged to be energized and controlled by the flow of electric current through the arc whereby said motor may be operated to automatically rotate the shaft and move the carriers 4 in proportion to the consumption of the carbons 6, in a manner well known in the art and requiring no particular description herein. Power is imparted from the motor to the shaft 2 by means of a worm 18 secured upon the shaft of the motor and arranged to mesh with a worm gear 19 rotatably mounted upon a sleeve 21 which in turn is rotatably mounted upon the outwardly extending end of the shaft 2. The sleeve 21 abuts against a collar 22 secured upon the shaft 2. A ratchet 23 is rotatably mounted upon the shaft and arranged to abut against the opposite end of the sleeve 21, said ratchet being held in frictional engagement with the sleeve by means of a suitable spring 24 compressed between the ratchet and a collar 26 secured upon the shaft 2, the pressure imparted by the spring 24 being sufficient to hold the ratchet in driving relation to the sleeve whereby a rotation of the ratchet will cause a corresponding rotation of the sleeve which is in turn imparted to the shaft 2 through the collar 22.

A cam 27 is connected to the worm gear 19 between said gear and the ratchet 23. A lever 28 is pivotally mounted as at 29 and arranged to rest upon the cam 27, the eccentricity of the cam being arranged to oscillate the lever 28 through a desired degree of movement when the gear 19 is rotated by the motor 17. A pawl 30 is pivotally mounted upon the lever 28 adjacent the ratchet 23, said pawl being arranged to engage the ratchet teeth 31 of said ratchet. The throw of the lever 28 and pawl 30 is arranged to cause the ratchet to be moved through a distance equal to the length of one tooth 31 for each revolution of the worm gear 19, the lever being lifted upwardly by the cam 27 to impart as positive driving force to the ratchet as shown in Fig. 5 of the drawings.

The shaft 2 extends outwardly past the ratchet 23 and is provided with a knob 32 whereby the shaft may be manually turned independently of the power actuating connections above described, the shaft 2 being rotatable within the sleeve 21 and ratchet 23 against the friction resistance resulting from the action of the spring 24.

In operation the carbons 6 are mounted

upon the carriers 4 in any suitable manner, 65 and adjusted to bring the adjacent ends into the desired proximity. As the carbons are consumed the motor, controlled by the flow of current forming the arc between the carbons, is energized and caused to rotate the shaft 2 very slowly, thereby causing the carriers to be advanced toward each other by means of the right and left hand threads formed thereon. The driving connections above described affords a very great reduction of speed, a great reduction being obtained through the worm 18 and gear 19. A single full rotation of the gear 19 operates to move the ratchet only through the length of one tooth and as a result the movement of the carriers along the shaft 2 is almost imperceptible even when the motor is operating at normal speed. The cam and ratchet mechanism permits this very great reduction of speed to be obtained in a very small space and with relatively few parts, thus obtaining a compact, economical and highly efficient mechanism. The shaft 2 is rotatable by means of the knob 32 independently of the power actuating mechanism, thus permitting a close manual adjustment of the carbon carriers regardless of whether the motor is in operation or not.

The carriers may be set or adjusted by simply depressing the handles 16 of the levers 12, thereby causing the threads of the shaft 2 to be disengaged and permitting the carriers to be quickly and easily moved to desired positions. This is an important feature of the invention as it greatly facilitates the resetting of the carriers and carbons and effects a big saving in time to the operator.

It is essential that the interruption necessary to accomplish the resetting of the carbons be kept at a minimum and the saving effected by my improved device is therefore of material advantage.

Should the carriers be inadvertently advanced to their extreme positions, my improved driving connection permits the rotation of the gear and ratchet to be continued without injury to any portion of the device, the frictional drive between the ratchet and shaft preventing damage to the motor or moving parts of the mechanism.

While I have illustrated and described what I now regard as the preferred form and construction of my invention, the specific details of construction are of course subject to modification in various ways. I therefore do not wish to restrict myself to the specific form and construction illustrated and described, but wish to avail myself of all modifications which may fall within the scope of the appended claims.

Having thus described my invention what I claim as new and desire to secure by Letters Patent is,

by the cam whereby the pawl may be actuated to rotate the ratchet and shaft; and a lever pivotally mounted upon each carrier and arranged to engage the threads of the shaft for moving the carriers relative to the shaft when said shaft is rotated, said levers being movable to disengage said threads and permit independent movement of either carrier in either direction independently of the rotation of the shaft.

8. In a carbon arc lamp, a threaded shaft; a pair of carbon carriers mounted in association with the shaft; a power actuated worm gear rotatably mounted upon one end of the shaft; a ratchet mounted adjacent the gear; means for holding the ratchet in frictional engagement with the shaft for rotating said shaft; a cam connected to the gear; a lever pivotally mounted adjacent

the cam; a pawl pivotally mounted upon the lever and arranged to engage the ratchet, said lever being arranged to be oscillated by the cam whereby the pawl may be actuated to rotate the ratchet and shaft; and a lever pivotally mounted upon each carrier and arranged to engage the threads of the shaft for moving the carriers relative to the shaft when said shaft is rotated, said levers being movable to disengage said threads and permit independent movement of either carrier in either direction independently of the rotation of the shaft; and means for normally holding the levers in engagement with the threads.

In witness whereof I hereunto set my signature.

WALTER G. PREDDEY.
